UNITED STATES PATENT OFFICE.

JAY CLAUDE LEWIS, OF CLEVELAND, OHIO.

CARBURETER.

No. 866,490.

Specification of Letters Patent.

Patented Sept. 17, 1907.

Application filed February 26, 1906. Serial No. 302,875.

To all whom it may concern:

Be it known that I, JAY CLAUDE LEWIS, a citizen of the United States, and a resident of Cleveland, county of Cuyahoga, and State of Ohio, have invented a new 5 and useful Improvement in Carbureters, of which the following is a specification, the principle of the invention being herein explained and the best mode in which I have contemplated applying that principle, so as to distinguish it from other inventions.

10 My invention relates to carbureters and particularly to that type of carbureter that is designed to prepare kerosene or ordinary coal oil as a fuel for internal combustion engines. This result has heretofore been only imperfectly accomplished, and the object of this my 15 present invention is to produce a device that will render available for the purpose above noted the less volatile constituents of petroleum such as kerosene.

To the accomplishment of the above object my invention comprises means hereinafter fully described 20 and particularly set forth in the claims.

The annexed drawings and the following description set forth in detail certain mechanism embodying the invention, said disclosed means constituting, however, but one of various mechanical forms in which the 25 principle of the invention may be used.

In said annexed drawings:—Figure 1 represents a central vertical cross-section of my improved form of carbureter; Fig. 2 represents in perspective the connections for supplying the fuel, *e. g.* kerosene, to said 30 carbureter; Fig. 3 is a plan view of a wick employed in connection with such carbureter; Fig. 4 is a broken perspective view of a portion of such wick shown in enlarged scale; and Fig. 5 is a longitudinal cross-section of the device taken on a plane through line 5—5, 35 Fig. 1.

My improved carbureter is an adaptation of the device described in my pending application, "Carbureter", Serial No. 245,122, whereby such device is designed to be made capable of using ordinary kerosene or coal oil instead of gas or gasoline for which the earlier device more particularly was planned.

As clearly shown in Fig. 1 my improved carbureter comprises as its base element a mixing chamber A which may be of any suitable size and construction.

40 As shown, it comprises two members, a lower member A' of a general cylindrical form, and an upper member A² secured thereon in the form of a cap having a neck provided with a central aperture. Said lower member is provided with an inlet opening whereby 45 air may be admitted into the chamber A. This opening is provided with a screen *a* held in place by an annular cap *a*² designed to prevent the entrance of dust or other impurities into the carbureter along with the air. Such air inlet is designed to be controlled 50 by means of a butterfly valve *a*³ that may be adjustably secured in place by means of a resilient flange *a*⁴ se-

cured on its stem and adapted to be operated with any one of a series of notches in an annular member *a*⁵. Such air inlet is further provided with a conical valve seat *a*⁶. Into this valve seat opens a hydro-carbon inlet *a*⁷, and formed in such seat is a shallow groove *a*⁹ extending part way around the same and communicating with the opening of the said inlet *a*⁷. This hydro-carbon inlet is controlled by device *a*⁸ similar to that employed in connection with butterfly valve *a*³. Transversely mounted across mixing chamber A above such valve seat *a*⁶ is a perforated diaphragm A⁵ preferably of the rounded form shown. This diaphragm is formed with a central downwardly projecting boss *a*¹² having a vertical aperture therein, 70 in which slidably fits the stem *a*¹¹, of an inverted mushroom valve A⁴ that is adapted to fit valve seat *a*⁶ and is firmly held therein by means of a spring *a*¹⁰.

Internally threaded into the neck of upper member or cap A² of mixing chamber A is a duct C. This duct 75 may be a single straight section of pipe or tubing, or preferably it may consist of a plurality of smaller ducts *c* as shown in Fig. 1, whereby the charge passing upwardly from the mixing chamber is subdivided into several columns for a purpose that will presently appear.

Externally threaded on the neck of the upper member or cap A² of mixing chamber A is a horizontally disposed perforated flange B. This flange is provided on its upper surface with an annular raised portion or 85 ridge B' formed with a deep narrow groove, Figs. 1 and 5. Apertures *b*² in flange B, diametrically opposite from each other, are connected with suitable ducts C' whereby liquid hydro-carbon fuel may be introduced into aforesaid groove *b*'. Within such groove 90 is fitted a circular wick B², the construction of which is shown in detail in Figs. 3 and 4. Such wick B² comprises several superimposed layers *b*⁷ of perforated asbestos, two as shown, held between strips *b*⁸ of perforated sheet metal. Mounted on such raised portion B' of flange B is an inner casing *b*³ closed at the top where it fits snugly around duct C, its lower portion being perforated as shown. On the outer side of such raised portion is similarly mounted another perforated casing *b*⁵ open at the top and of a height a trifle less than that of casing *b*³. Said casings *b*³ *b*⁵ 100 may be fitted either on opposite sides of the groove in such raised portion B', or respectively on the inside and outside of such raised portion itself. In either event it is seen that wick B² lies in between them. Surrounding the whole of this portion of the device is a solid outer case B³ secured on the periphery of the flange B at its lower end, and provided at its upper 105 end with a ventilator cap B⁵ of which an improved form is the one shown consisting of two separate members *b*⁹ *b*¹⁰ arranged in the manner clearly shown in Fig. 1.

While the feed connections, whereby kerosene or other hydro-carbon is supplied to hydro-carbon inlet a^7 and burner inlets b^2 b^2 , may be varied to suit circumstances, I have found it desirable to connect both 5 such inlet and burner to a common source of supply. The arrangement of ducts whereby to effect such connection is clearly shown in Fig. 2. In such figure pipe C^2 leads from the supply tank; this main supply pipe is provided with two branches C^3 C^4 , the first of 10 which leads to the feed apertures of the burner through pipes C' , the second of which leads to the hydro-carbon inlet of the mixing chamber. Interposed in the latter is a reservoir C^5 , the purpose of which is to accumulate and hold in store a sufficient quantity of the fuel to 15 supply the inlet of the mixing chamber without by any possibility withdrawing from the burner its full quota of fuel; otherwise when the engine is running at full speed, the suction from the mixing chamber is apt to use the oil so rapidly that the branch pipe leading 20 to the burner is left practically dry.

The operation of my carbureter is readily apparent from the foregoing description. The suction of the engine in its intake stroke will raise valve A^4 against spring a^{10} and draw in a quantity of air. Such air in 25 passing between the valve and its seat is drawn across the opening of the hydro-carbon inlet a^7 and groove a^9 communicating therewith and so takes up a quantity of the liquid and carries the same along into the mixing chamber A in the form of a mist. The perforated dia- 30 phragm A^5 serves to still further comminute the particles of oil. The mist laden air next passes through the duct C which, as has been stated, may be either a single straight tube or preferably composed of a plurality of smaller tubes. Such duct is maintained 35 by means of the burner that surrounds it at a sufficiently high temperature to vaporize or gasify the hydro-carbon contained in the charge. The charge thereupon passes into the engine cylinder and is there exploded.

It is thus seen that by means of the above described 40 apparatus, I am enabled to make of kerosene or coal oil a most efficient fuel for internal combustion engines. The oil is not only entirely vaporized so as to present all the properties of a gas, but is further raised to a temperature that insures its more thorough and 45 rapid combustion in the engine cylinder with a consequently increased production of power.

Obviously the results here noted as having been obtained by means of my improved carbureter in the use of kerosene in connection with internal combustion engines would similarly commend its use where other fuels of a more or less similar character are thus sought to be utilized. Accordingly, wherever kerosene, or the more general term hydrocarbon, has been employed either in the preceding specification or the 50 following claims, such terms will be understood to include under the rule of equivalents any suitable fuel material adapted to be employed in a manner similar to that here described.

Having thus described my invention in detail, that 60 which I particularly point out and distinctly claim is:—

1. In a carbureter, the combination of a mixing chamber, a duct leading therefrom, a hydrocarbon burner sur-

rounding said duct and adapted to heat the same, means for supplying hydrocarbon to said burner, and a casing laterally inclosing said burner and duct. 65

2. In a carbureter, the combination of a mixing chamber, a duct leading therefrom, a hydrocarbon burner surrounding said duct, means for supplying liquid hydrocarbon to said burner, a perforated casing inclosing said burner, and an outer solid casing laterally inclosing said 70 perforated casing.

3. In a carbureter, the combination of a mixing chamber, a duct leading therefrom, a perforated flange surrounding said duct, a hydrocarbon burner mounted on the upper face of said flange and surrounding said duct, means for supplying hydrocarbon to said burner, a perforated casing inclosing said burner, and a solid casing secured to the periphery of said flange and laterally inclosing said 75 perforated casing.

4. In a carbureter, the combination of a mixing chamber, a duct leading therefrom, a perforated flange surrounding said duct and having a groove adapted to receive a wick, means for supplying liquid hydrocarbon to said groove, a perforated casing on each side of said groove, and an outer solid casing secured to the periphery of said flange and laterally inclosing said 80 perforated casings. 85

5. In a carbureter, the combination of a mixing chamber, a duct leading therefrom, said duct being subdivided for a portion of its length, a perforated flange surrounding said duct just below such subdivided portion and having a groove adapted to receive a wick, means for supplying liquid hydrocarbon to said groove, a perforated casing on each side of said groove, and an outer solid casing secured to the periphery of said flange and laterally inclosing said 90 perforated casings. 95

6. In a carbureter, the combination of a mixing chamber, a duct leading therefrom, said duct being subdivided for a portion of its length, a perforated flange surrounding said duct just below such subdivided portion and bearing on its upper side a grooved annular ridge adapted to receive a wick, connections for supplying liquid hydrocarbon thereto, a perforated cylindrical casing attached to each side of said ridge, the inner of said casings being closed at the top, and an outer solid casing secured to the periphery of said flange and laterally inclosing said 100 perforated casings. 105

7. In a carbureter, the combination of a mixing chamber, a duct leading therefrom, said duct being subdivided for a portion of its length, a perforated flange surrounding said duct just below such subdivided portion and bearing on its upper side a grooved annular ridge adapted to receive a wick, connections for supplying liquid hydrocarbon thereto, a perforated cylindrical casing attached to each side of said ridge, the inner of said casings being closed at the top, an outer solid casing secured to the periphery of said flange and laterally inclosing said 110 perforated casings, and a ventilator cap secured to the top of such outer casing. 115

8. In a carbureter, the combination of a mixing chamber, having an air inlet and a hydrocarbon inlet, a duct leading from said mixing chamber, a hydrocarbon burner surrounding said duct and adapted to heat the same, and means connecting said hydrocarbon inlet and burner with a common source of supply. 120

9. In a carbureter, the combination of a mixing chamber having a hydrocarbon inlet, a duct leading from said mixing chamber, a hydrocarbon burner surrounding said duct and adapted to heat the same, a branched connection, the branches thereof leading to the hydrocarbon inlet of said mixing chamber and to said burner, respectively, and a reservoir interposed in the branch of said 130 connection leading to said inlet.

Signed by me, this 24th day of February 1906.

J. CLAUDE LEWIS.
